DEVICE FOR REPAIRING AUTOMOBILE BODY MEMBERS AND THE LIKE

Erwin Max Zinke, Oakland, Calif.

Original application December 22, 1950, Serial No. 202,278. Divided and this application December 17, 1952, Serial No. 336,695

3 Claims. (Cl. 287—54)

1

This invention relates to an improved device for repairing automobile body members and the like. This application is a division of my earlier-filed application, Serial Number 202,278, filed December 22, 1950, which was a continuation-in-part of application Serial Number 124,712, filed October 31, 1949, and issued on December 2, 1952, as Patent Number 2,620,011.

This invention solves the problem of providing clamp members that can grip a variety of surfaces from a variety of different positions and which can rapidly be adapted to these different requirements. This problem has been solved by a novel grip member that is explained below.

These and other features will appear from the following detailed description of a preferred embodiment of the invention, reference being had to the accompanying drawings. It should be understood, however, that the drawings and descriptions are illustrative and are not intended to narrowly limit the scope of the invention, which is defined in the appended claims.

In the drawings:

Fig. 1 is a view in side elevation showing a jack in use with a pair of grip clamps embodying the principles of the present invention. A portion of a dented automobile hood, which is to be straightened, is shown in dotted lines. The grip clamps are identical, but their jaws are turned in different directions, as required by the object being gripped.

Fig. 2 is an enlarged view in perspective of the grip clamp with the jaw set as in the position shown at the left hand side of Fig. 1.

Fig. 3 is an enlarged view in perspective of the grip clamp with the jaws set in the position shown at the right hand side of Fig. 1.

Fig. 4 is a view in elevation and in section taken along the line 4—4 of Fig. 3.

Fig. 5 is a view in section taken along the line 5—5 of Fig. 3.

Fig. 6 is a top plan view of the clamp showing the right angle positions of the jaws. In dotted lines the jaws are shown in the position illustrated in Fig. 2, while the solid lines show the jaws in a position 180° opposite therefrom.

Grip clamp

When a part is to be gripped firmly and either pushed or pulled, a very useful feature of this invention is a novel grip clamp which may be used on one or both ends of a jack 10. Fig. 1 shows two identical clamps being used with the jack 10 which is preferably a jack like the one disclosed in the parent application, S. N. 202,278,

5 filed December 22, 1950. The two clamps are attached to the jack, one at each end, while Figs. 2—6 show the clamp in more details.

In Fig. 1 an automobile body member 103 has been smashed in, and it is desired to push it back to shape. One gripper clamp 101a has been threaded on a rod 20, which is extending out the front of the jack 10. The other gripper clamp 101 has been secured to a tubular extension member 102, which has been threaded into the rear bushing 56 of the jack 10. The jack 10 itself has a body 11 with a handle 49 fitting in a socket 40 in a yoke arm 14 which is part of the body 11 opposite the upwardly extending portion 12. The jack has a front bushing 53 and a rear bushing 56. The rod 20 is movable through the jack 10 and through the stationary extension 102, so that the distance between the clamps 101 and 101a can be changed by pumping the jack handle.

10 Figs. 2—6 show the clamp 101 (or its identical clamp 101a) in various views. Each clamp 101 consists of five pieces: a base piece 103, a pair of jawed clamp arms 104, 105, and a nut and bolt assembly 106, 107.

15 The base piece 103 is preferably made from aluminum, for lightness. It may have two or more tubular sockets 110, 111 which are preferably at right angles to each other. Both sockets 110, 111 may be threaded, preferably oversize and overlength with respect to the fitting they receive. In that way the pipe 102 which fits in them may bury its threads and not have a weak portion extending outside the socket. The threads of the bushings 53, 56 may be similarly constructed. The fact that the pair of sockets 110, 111 are at right angles to each other gives great adaptability, making its installation possible in many types of places where one or other of the sockets could not be used.

20 Beyond the sockets 110 and 111, the base piece 103 has a cross-channeled portion 112, adapted to receive the arms 104, 105 in any of three positions. The cross-channeled portion 112 has two identical faces on its opposite sides. Each face includes a central, unthreaded, stud 113 and four corner posts 114, 115, 116, and 117. Two cross channels 118 and 119 are thereby provided, lying between the posts: an axial channel 118 and a transverse channel 119.

25 The arms 104, 105, which are preferably made from spring steel, each have a substantially flat strap 120 that is adapted to rest on one face of the cross-channeled portion 112 of the base plate 103. The strap 120 is only slightly narrower than the channels 118, 119 and is perforated at

121 to receive the stud 113. Each arm 104, 105 has a curved jaw 122 that preferably terminates in a roughened gripping surface 123. Each jaw 122 has a perforation 124 that extends through it at the top of its arc. When the jaws 122 are joined together, they are held in gripping position by the bolt 106 passing through the perforations 124 and fastened by the nut 107.

The base 103 and arms 104 and 105 are so adapted that the arms may lie in any one of three positions: axial or transverse to either side. The straps 120 may be held in the axial channels 118 or may be held in either direction in the cross channels 119. In any of these positions, the strap 120 will engage the stud 113 and will also contact the four corner posts 114, 115, 116, and 117. Sideward thrust will be taken up by the stud 113 and two diagonally opposite corner posts, which turn depending on the direction of thrust.

In operation, the clamp 101 is threaded on either the rod 20 or on a fitting 102. Either socket 110 or 111 may be used, depending on which is more convenient under the circumstances. The arms 104, 105 are positioned in any one of its three possible directions, by loosening the nut 107, placing first one arm 104 over the stud 113 and positioning it either in the axial channel 118 (either direction) or in the transverse channel 119, and then positioning the other arm 105 in the same channel and same direction on the opposite side. Then the nut 107 is tightened on the bolt 106. It is unnecessary to remove the nut 107 completely during this operation; if the nut 107 is simply loosened, the clamp arms 104, 105 are easier to position than if the nut 107 is removed. The clamp jaws 120 are positioned on the two sides of the object to be clamped, and the gripping surfaces 122 are tight-

ened against it by tightening the nut 107 on the bolt 106. It takes only a few seconds to change the clamp from one channel 118, 119 to the other, or to reverse the direction in channel 118.

I claim:

1. A grip clamp, including in combination: a base piece having a socket for securing it to another member and having at one extremity a cross-channeled face on each of two opposite sides, each said face having a central stud projecting outwardly from said face and four corner posts defining two mutually perpendicular channels thereacross; a pair of clamp arms having at one end a strap adapted to fit in said channels, said strap having a central opening adapted to receive said stud and having a width only slightly smaller than the distance between adjacent corner posts, each said clamp arm also having a clamp jaw at its opposite end; and means to urge said clamp arms toward each other to hold their straps on said base piece and their jaws against an object to be gripped.

2. The clamp of claim 1 in which there are two sockets in said base piece, lying mutually perpendicular.

3. The clamp of claim 2 in which one socket lies along the axis of the clamp and the other one is radial thereto, and parallel to said studs.

ERWIN MAX ZINKE.
